UNITED STATES PATENT OFFICE.

HARRY N. COVELL, OF NEW YORK, N. Y., ASSIGNOR TO LIDGERWOOD MANUFACTURING COMPANY, A CORPORATION OF NEW YORK.

BRAKE-BAND.

No. 812,827.

Specification of Letters Patent.

Patented Feb. 20, 1906.

Application filed July 22, 1904. Serial No 217,651.

To all whom it may concern:

Be it known that I, HARRY N. COVELL, a citizen of the United States, and a resident of the city of New York, borough of Brooklyn, in the county of Kings and State of New York, have invented a new and useful Improvement in Brake-Bands, of which the following is a specification.

My invention relates to brake-bands, and is intended for use principally with hoisting-engines.

It consists of certain novel parts and combinations of parts pointed out in the claims concluding this specification.

15 Heretofore it has been the practice in setting the friction members in driving contact to employ a hand-wheel constructed with a ratchet and pawl, the pawl usually being operated by a spring. It has been found, 20 however, with this ratchet-and-pawl construction that the jar of the hoisting-engine was so great that the pawl would be thrown out of place and the friction-screw used for setting the rope-drum which was operated 25 by said pawl would not hold in the position to which it was set. It is one of the objects of my invention to remedy this defect.

Reference being had to the drawings, Figure 1 is a sectional elevation of a rope-drum 30 with my invention applied thereto. Fig. 2 is an end view, partly in section, of a wheel embodying my invention.

The following is a description of the brake-band and wheel shown in the accompanying drawings, which illustrate the form in which I at present prefer to embody my invention. It will be understood, however, that various modifications and changes may be made in the details of the same without departing 40 from my invention and without exceeding the scope of the concluding claims. I have shown the brake-band applied to a hand-wheel, but do not wish to limit myself to this operating means, as others may be employed.

1 and 2 are stationary end frames carrying bushings 3 and 4, in which the shaft 5 is journaled. The shaft 5 is held against longitudinal movement by flanges on the interior 50 of the bushing 4, these flanges projecting into the grooves 6 and 7 of the shaft, and also by the shoulder 8 of the shaft bearing against the face of the frame 2, the collar 9 fixed to the end of the shaft and which bears against

the opposite face of frame 2, and the shoulder 55 10 of the shaft between the face of frame 1 and clutch member 11.

The clutch member 11 is fixedly secured to the shaft 5 and has fastened to it the friction-ring 12, preferably composed of sections 60 of wood.

13 is a rope-drum carrying the flange 14, containing a groove which co-operates with the friction-ring to form the friction-clutch. The drum 13 is mounted loosely upon the 65 shaft.

Interposed between the fixed clutch member 11 and the drum 13 and tending to hold the drum disengaged from the fixed member when not acted upon by the mechanism used 70 for applying the friction is the spring 15.

16 is a cross-key interposed between the drum 13 and the shoulder 8 of the shaft. 17 is a pin which abuts against said cross-key and extends through an opening at the center 75 of the shaft, projecting from one end thereof in position to be operated by the screw 18, threaded in the nut 19, fixed to frame 2.

To take care of friction upon the thrust-pin 17, I employ a lubricating-box 20, similar to 80 that described in patent to Beckman, No. 541,308, for containing a lubricant to immerse the bearing-surface between the thrust pin 17 and the screw 18. The friction-screw 18 is operated by means of the hand-wheel or 85 other means 21, affixed thereto. Cast on said wheel is a flange 22, upon which is placed a brake-band 23, preferably of steel.

24 24^a are supporting-arms which are suitably secured to the frame 2. These arms extend downward and at their lower ends are made fast to the pin or bolt 25, which is secured to the frame 2. Fulcrumed to the pin 25 is the bell-crank lever 26. One arm 27 of this lever has secured to it the end 28 of the 95 brake-band 23. The other arm 29, which forms a treadle with a foot-piece 34, has a projection 30 thereon, to which is screw-threaded and secured, by means of the nut 31, the end 32 of the brake-band. This end 32 100 passes through an opening 33 in the end 28 of the brake-band. A bracket 35, which is part of the support 24, has adjustably secured to it the spring 36, which is attached to the end 29 of the lever. This spring tends to hold 105 the lever in an upright position, and thereby prevents the brake-band from slipping.

The operation of the device is as follows:

With the wheel and brake in the position shown by the drawings the wheel may be turned in one direction, in the present instance clockwise. This turning will cause 5 the screw 18 to operate, which in turn will operate upon the pin 17. This pin being acted upon will bear against the key 16, which bears against the drum 13 and will push said drum against the spring 15 until the groove 10 of the flange 14 frictionally engages with the ring 12 and clutches the same. By this means the drum may be set to the desired position and will remain in that position, the brake-band preventing the wheel from turning 15 backward and releasing the friction-screw and the mechanism which operates to set the drum. When it is desired to release the clutch mechanism, it may be done by operating the treadle. Bearing down on this treadle 20 will cause the arm 27 and the end 28 of the brake-band to rise. At the same time the other arm 29 and the end 32 of the brake will be lowered and the brake-band will release its hold on the wheel, permitting it to be turned 25 backward, and thus bringing the drum out of its frictional engagement with the ring 12.

Having thus described my invention, what I claim, and desire to secure by Letters Patent, is—

1. The combination with friction clutch members of a device for setting said members in driving contact and means independent of the setting mechanism automatically operating to retain said device and clutch members 35 in driving contact.
2. The combination with friction clutch members of a device for setting said members in driving contact, means independent of the setting mechanism automatically operating 40 to hold said device and clutch members in set position, and means whereby said device may be released to permit the unsettling of said clutch members.
3. The combination with friction clutch 45 members, of a device for setting said members in driving contact, and a brake-band

whereby said device is free to turn in one direction and held from turning in the opposite direction.

4. In combination with friction clutch 50 members, a wheel for setting said members in driving contact, a brake-band thereon permitting the turning of said wheel to set said members and automatically operating to restrain said wheel from turning in the reverse 55 direction.

5. The combination with friction clutch members, of a device free to turn to set said members in driving contact, a brake-band whereby said device is restrained from turning 60 in the reverse direction and means whereby said brake-band may release said device to turn in the opposite direction.

6. The combination with friction clutch 65 members of a device for setting said members in driving contact, a brake-band thereon normally holding said members in set position and means whereby said brake-band may release said device and permit the unsettling of said members.

7. The combination with friction clutch 70 members, of a device for setting said members in driving contact, a brake-band thereon normally holding said device from backward turning, and a treadle for releasing said 75 brake-band thereby permitting the turning of said device in reverse direction.

8. The combination with friction clutch members, of a device for setting said members in driving contact, and a brake-band 80 thereon, the ends of said brake-band being attached to a lever, said brake-band normally holding said device in set position until released by action upon said lever.

In testimony whereof I have signed my 85 name to this specification in the presence of two subscribing witnesses.

HARRY N. COVELL
